PUMP TO MOTOR ADAPTER

Allen M. Ruliffson, 1411 Morena, San Diego, Calif.

Filed Oct. 21, 1965, Ser. No. 87,665

Term of patent 14 years

(Cl. D65—1)

I claim:

The ornamental design for a pump to motor adapter, as shown.
